His Attorney

UNITED STATES PATENT OFFICE.

CLIFFORD SKLAREK, OF CHICAGO, ILLINOIS, ASSIGNEE TO INTERNATIONAL SPOT-LIGHT CORPORATION, OF CHICAGO, ILLINOIS, A CORPORATION OF ILLINOIS.

LAMP HEAD.

Application filed March 12, 1923. Serial No. 624,376.

This invention relates to improvements in lamp heads.

One object of the invention is to provide a lamp head particularly adapted for use in connection with automobiles, wherein means is provided for adjusting the lamp bulb with reference to the parabolic reflector, to obtain a true focus of the light rays.

Another and more specific object of the invention is to provide a lamp head of the character indicated, wherein the parabolic reflector is provided with a sleeve, rigid therewith, slidably receiving the bulb-holding socket for adjustment therein.

A further object of the invention is to provide a lamp head of the character indicated, with means for adjusting the bulb holding lamp socket with reference to the reflector, wherein the means for manipulating the adjusting means is located exteriorly of the head, where it is readily accessible to the operator.

A still further object of the invention is to provide a lamp head of the character indicated, wherein all joints are effectively sealed to prevent moisture from entering the head.

A specific object of the invention is to provide, in a lamp head having a reflector, means for supporting and guiding a lamp bulb with respect to the reflector, in such a manner that the adjustment or position of the lamp bulb cannot be injuriously affected as a result of shrinkage of insulating material.

Other objects and advantages of the invention will more clearly appear from the description and claims hereinafter following.

In the drawing, forming a part of this specification, Fig. 1 is a front elevational view of a lamp head showing my improvements therewith. Fig. 2 is a vertical, longitudinal, sectional view, taken substantially on a plane passing diametrically through the lamp head, certain parts being shown in elevation. Fig. 3 is a detail sectional view, corresponding substantially to the line 3—3 of Fig. 1; and Fig. 4 is an enlarged, detail, longitudinal vertical sectional view of the lamp socket, sleeve and adjacent parts shown in Fig. 2.

In said drawing, 10 indicates a generally bowl-shaped sheet metal shell forming a

housing for the parts of the lamp head.

The rear end of the shell 10 is provided with an integral, outwardly drawn, hollow protuberance 11, for a purpose hereinafter described. At the outer side, the shell 10 is provided with an integral, annular peripheral rim 12 as clearly shown in Fig. 3. The rim 12 is in the form of a flange of right angular cross section comprising an annular flat portion 13 extending outwardly at right angles to the adjacent cylindrical end portion 14 of the shell 10, and a rearwardly extending cylindrical portion 15 spaced from the cylindrical portion 14 and parallel thereto.

Housed within the shell 10 is a parabolic reflector 16 provided with a central perforation 17 adapted to snugly receive the reduced end 18 of a cylindrical metal sleeve 19, the outer edge of the sleeve being swaged over the edge of the perforation to rigidly secure the sleeve to the reflector. The outer edge of the reflector 16 is expanded to provide an integral annular rim 20 and an annular shoulder 21 extending at right angles to the rim. Inwardly of the shoulder, the adjacent portion of the reflector 16 is of an external diameter to snugly fit within the outer cylindrical end portion 14 of the shell 10, and hold the reflector properly centered within the shell 10, with the shoulder 21 thereof in abutment with the rim 12 of the shell.

The lamp head is provided with the usual disc shaped lens 22, which is held in position by a flanged clamping ring 23 of U-shaped cross section. The clamping ring 23 is of split form as clearly shown in Fig. 1, and is provided with perforated lugs 24 adjacent the split, adapted to receive a clamping bolt 25 by which the ring is positively held in closed position. To prevent moisture from entering the shell at the joint between the same and the lens 22, an annular gasket 26 is interposed between the rim of the lens and the shoulder 21 of the reflector 16. As clearly shown in Fig. 3 the outer annular flange of the clamping ring 23 is adapted to over-lap the periphery of the lens, while the inner flange thereof engages in back of the portion 15 of the rim 13 of the shell, thus holding the lens, gasket and reflector tightly clamped against the rim 13 of the shell 10.

Slidably mounted within the sleeve 19, for adjustment relative to the parabolic reflector, is a lamp socket 27. The lamp socket 27 includes a cylindrical metal shell 28 having a flanged metal cap 29 rigidly secured at one end thereof, and a spring pressed, cylindrical metal plug 30 slidably mounted within the shell. As clearly shown in Fig. 4, the shell 28 is of a greater length than the sleeve 19 and projects beyond the rear end thereof, and the cap 29 is provided with an enlarged bore as indicated at 31 adapted to loosely receive the free end of the sleeve 19. The cylindrical plug 30 comprises a cup 32 adapted to receive a tightly fitting cylindrical block of insulating material 33, provided with a central bore 34 adapted to receive a tightly fitting, cylindrical metal plug 35, with the inner end of the latter slightly spaced from the bottom of the bore 34. The plug 35 and the cup 32 may be formed of any suitable metal but are preferably made of brass. The block of insulating material 33 is also provided with a lateral opening 36 communicating with the bore 34, and the cup 32 is provided with a laterally extending screw threaded opening 37, axially aligned with the opening 36 and of relatively greater diameter. A threaded plug 38, provided with an axial bore, is rigidly secured to the cup 32 by being screwed into the opening 37. The shank of the plug 38 extends through aligned guide slots 39 and 40, in the shell 28 and the sleeve 19 respectively, and serves as a stop to limit the outward movement of the plug 30 within the shell 28, by engagement with the outer end of the slot 39. The cylindrical metal plug 35 is provided with an axial threaded opening therethrough, adapted to receive the contact screw 41.

As clearly shown in Fig. 4, the insulated conductor 42 is extended through the bore of the plug 38 and the aligned opening 36 of the block of insulation, with the stripped end 43 thereof clamped between the inner end of the contact screw 41 and the bottom of the bore 34.

To yieldingly press the plug 30 in outwardly projected position and hold the contact screw 41 in abutment with the contact point on the lamp bulb 48, a spring 44 is interposed between the inner face of the cap and the inner end of the plug 30. The sleeve 28 is provided with the usual bayonet slots 45 shown in dotted lines in Fig. 4 which are adapted to receive and co-act with the pins 46 projecting at diametrically opposite sides from the metal collar 47 of the lamp bulb 48.

To provide for adjustment of the lamp socket 27 and the bulb 48 with respect to the parabolic reflector 16, to effect a proper focusing of the light rays, an adjusting screw 49 is provided. The adjusting screw 49 is rotatably mounted in an opening 50 in the protuberance 11 of the housing, and is pro-

vided at the outer end thereof with a rigidly connected operating head or knob 51, abutting the outer side of the protuberance. Internally of the housing, the screw 49 is provided with a collar 52 adapted to abut the inner side of the wall of the housing. The collar 52 together with the head 51 act as a means for preventing longitudinal movement of the adjusting screw. The threaded end 53 of the adjusting screw 49 is adapted to work in a threaded recess 54 in the cap 29. A coiled spring 55 is interposed between the peripheral flange 56 of the cap 29 and the inner side of the end wall of the protuberance 11, and serves to press the socket outwardly, thereby producing sufficient friction between the screw and the cap and between the knob 51 and the housing to prevent accidental turning of the screw, which might result in disturbing the adjustment of the socket.

To prevent moisture from entering the shell by way of the joint between the screw 49 and the wall of the opening 50, the head or knob 51 is provided with an annular channel 57 adapted to receive a packing washer 58. The washer 58 is preferably saturated with pure petroleum to effectively obstruct the passage of moisture between the same and the outer end of the protuberance 11. In this connection, it is pointed out that the gasket 26 which is interposed between the lens 22 and the reflector 16 may also be treated in this manner, if desired.

The housing 10 is provided at one side thereof with an outwardly drawn portion as indicated at 59, perforated as indicated at 60 to receive a hollow metal plug 61, the joint between the plug and the shell 10 being soldered or otherwise sealed to prevent the entrance of moisture.

In this connection it is pointed out that the entrance of moisture into the shell 10 is effectively prevented by forming a tight joint between the one piece shell 10 and the plug 61, and providing, as hereinbefore described, the water-seal gaskets, in the joint between the shell and the knob 51, and in the joint between the reflector 16 and the lens 22.

The hollow plug 61 extends at right angles to the horizontal axis of the lamp head, as clearly shown in Fig. 2 and the conductor 42 is adapted to be passed therethrough. At the outer end, the hollow portion of the plug 61 is reduced in diameter as indicated at 62 and the conductor 42 is adapted to extend therethrough, a sleeve 63 of insulating material being interposed between the conductor and the inner wall of the reduced hollow portion 62. A metal contact plug 64 may be attached to the end of the conductor, said plug being surrounded by the insulating sleeve 63 and having its outer end projecting a short distance beyond the end of the sleeve and serving as a means for connecting the

conductor 42 to the lighting circuit, as shown in my co-pending application Serial Number 525,076, filed December 27, 1921.

To adjust the lamp bulb with reference to the parabolic reflector to properly focus the light rays, the feed screw 49 is rotated in either a right or left hand direction, in accordance with the direction in which it is found necessary to adjust the bulb, the screw being properly manipulated by means of the head or knob 51, thereby moving the bulb either toward or away from the reflector. As the threads 53 are in direct engagement with the cap 29, which is rigidly secured to the sleeve 28, the sleeve 28 together with all the parts carried thereby, including the lamp bulb, which is held in fixed position with reference to the sleeve by the spring pressed plug 30 holding the pins 46 in abutment with the outer ends of the inner branches of the bayonet slots, will be positively adjusted, as a unit. In this connection it will be noted that the slot 40 in the sleeve 19 in which the plug 38 slides, is of sufficient length to permit the maximum movement necessary to effect the proper adjustment of the bulb.

By rigidly securing the sleeve 19 to the parabolic reflector 16, as hereinbefore described, the lamp socket 27 which is positively guided in its sliding movement by the sleeve, will always move in a fixed path with reference to the reflector, regardless of any slight displacement of the reflector with reference to the housing, and a true focus may therefore always be obtained.

Another important feature of my invention is the construction of the spring pressed plug 30, in that the conductor is directly connected to the plug by being positively clamped by the contact screw 41 which engages directly with the contact point of the lamp bulb, whereby the current is directly transmitted independently of the sliding parts by which the position of the bulb is adjusted; and in that the contact screw is carried directly by the brass plug which is mounted in the insulation 33, which in turn is mounted in the brass cup 32 whereby, variations due to shrinkage of the insulating material do not affect the position of the outer end of the contact screw.

It will also be noted that all of the parts which are in sliding contact are of metal so that wear is reduced to the minimum with consequent minimization of danger of looseness or play and permitting of accurate fitting and finish of the parts in the original assembly.

I have herein shown and described what I now consider the preferred manner of carrying out the invention, but the same is merely illustrative and I contemplate all changes and modifications that come within the scope of the claims appended hereto.

I claim:

1. In a device of the character described, the combination with a reflector; of a water tight housing enclosing said reflector and having a portion spaced therefrom; guide means extending between said reflector and the adjacent portion of said housing; a lamp socket member slidably mounted in said guide means; a headed adjusting screw extending through the adjacent wall of said housing and coacting with the socket member to adjust the latter, the head of said screw being exterior of the adjacent wall of said shell and adapted to bear thereon, the head of said screw being provided with a recess for the reception of packing to render the housing water tight at this point. 75

2. In a device of the character described, the combination with a lamp housing; of a reflector mounted therein; a lamp carrying member movably supported with reference to said reflector to permit adjustment of the focus; and a rotatably mounted adjusting element extending through an opening in said housing and operatively connected to said carrying member, said element having an exterior head by which said adjusting element is rotated, said head being provided with a recess containing packing adapted to engage the housing and close the opening through which said adjusting element extends to render the housing water-tight at this point. 85

3. In a device of the character described, the combination with a reflector; of a housing enclosing said reflector and having a portion spaced therefrom; a guide sleeve rigidly connected with said reflector and terminating short of the adjacent wall of said housing, said sleeve having a longitudinal slot therein; a lamp carrying sleeve slidably mounted in said guide sleeve and provided with a slot registering with the slot in said guide sleeve, said sleeve being arranged to have a lamp detachably secured at one end; a 100 cup shaped cap having a bottom and a side wall, said cap being rigidly secured to said carrying sleeve and having its bottom closing the opposite end of said carrying sleeve, the side wall of said cap slidably fitting over the exterior of the outer end of said guide sleeve and having outwardly turned flanges thereon; a contact plug slidably disposed in said carrying sleeve; a conductor extending through the slots in said sleeves and connected with said plug and arranged to prevent relative rotation of said carrying sleeve with respect to said guide sleeve; resilient means interposed between the bottom of said 105 cap and the plug for urging said plug toward said lamp; resilient means interposed between the wall of said housing and the outwardly turned flanges of said cap; and an adjusting screw threaded into said cap 110 and rotatably mounted in said wall for effect- 115

125

130

ing longitudinal movement of said carrying sleeve and its associated parts in unison.

4. In a device of the character described, the combination with a reflector; of a housing enclosing said reflector and having a portion spaced therefrom; a guide sleeve rigidly connected with said reflector and terminating short of the adjacent portion of the housing; a lamp carrying sleeve slidably mounted in said guide sleeve and arranged to have a lamp detachably secured at one end, said sleeve being of a length to project rearwardly beyond the terminus of said guide sleeve; a cap rigidly secured to said carrying sleeve and having forwardly extending portions fitting over the rear end of said guide sleeve; a contact plug slidably disposed in said carrying sleeve; resilient means interposed between the inner surface of said cap and said contact plug; resilient means interposed between the adjacent portion of said housing and the forwardly extending portions of said cap; and an adjusting screw extending through the spaced portion of said housing and threaded into said cap.

5. In a device of the character described, the combination with a reflector; of a housing enclosing said reflector and having a portion spaced therefrom; a guide sleeve rigidly connected with said reflector and terminating in an open end short of the adjacent wall of said housing, said sleeve having a longitudinally extending slot therein; a lamp carrying sleeve slidably mounted in said guide sleeve and provided with a slot registering with the slot in said guide sleeve, said carrying sleeve having holding means arranged to detachably secure a lamp at one end, and having a wall at its opposite end normally arranged beyond the terminus of the rear end of said guide sleeve and closing the open end of the latter; a contact plug slidably disposed in said carrying sleeve; a conductor extending through the slots in said sleeves and connected with said plug and arranged to prevent relative rotation of said carrying sleeve with respect to said guide sleeve; a lamp disposed in said holding means; resilient means interposed between the inner surface of said end wall and the plug for urging the latter into engagement with the contact means of said lamp and serving to maintain said lamp against accidental detachment from said holding means; additional resilient means interposed between the spaced portion of said housing and the exterior surface of said end wall, both of said resilient means being confined substantially to the space between the terminus of said guide sleeve and the adjacent portion of said housing, said additional resilient means pressing said carrier sleeve toward said guide sleeve; and an adjusting screw threaded into said wall and rotatably mounted in said housing for effecting move-

ment of said carrying sleeve and its associated parts in unison.

6. In a device of the character described, the combination with a reflector; of a housing enclosing said reflector and having a portion spaced therefrom; a lamp carrying sleeve having holding means arranged to detachably secure a lamp adjacent the forward end; a cap closing the rear end of the sleeve and having an outwardly extending projection formed on its exterior, guiding means rigid with the reflector and permitting relative adjustment of the lamp carrying sleeve with relation to the reflector; a contact plug slidably disposed in said carrying sleeve and adapted to co-operate with the lamp; an adjusting member carried by said housing and connected with the rear end of said cap for imparting longitudinal movement thereto and to the sleeve; resilient means interposed between said contact plug and the inner face of the cap and serving to maintain engagement of said contact plug with the lamp, and to secure said lamp against accidental detachment with respect to said holding means; and additional resilient means interposed between the spaced portion of said housing and the projection on said cap at the rear end of said lamp carrying sleeve, both of said resilient means being arranged concentrically and extending substantially at right angles to the longitudinal axis of said lamp carrying sleeve.

7. In a device of the character described, the combination with a reflector and a housing having a wall spaced from said reflector; a guide sleeve rigidly secured to said reflector, extending toward the adjacent portion of said housing and terminating short thereof; a carrying sleeve unit, comprising: a member open at its forward end and closed at its rear end, said carrying sleeve being telescopically engaged with said guide sleeve and longitudinally movable as a whole with respect to said guide sleeve, the latter and said carrying sleeve being provided with registering slots intermediate their ends, and the forward end of said carrying sleeve being provided with bayonet slots adapted to have a lamp detachably disposed therein, one pole of which is grounded on said sleeves, said carrying sleeve having a contact plug slidably disposed therein, and insulated therefrom, said plug being connected with a conductor extending outwardly through said slots to a source of electric supply, and a coil spring in said carrying sleeve interposed between the rear wall of the latter and insulated from said contact plug and bearing upon the latter to urge the same into engagement with the other pole of said lamp, and exerting pressure on said lamp to resiliently maintain the same in said bayonet slots; and

an adjusting member rotatably mounted in the housing wall and having a threaded portion in threaded engagement with the rear end of said carrying sleeve and extending 5 into the latter and into the coiled spring therein, said adjusting member serving to maintain said carrying sleeve in position

and to adjust the same, with the associated lamp and contact means, longitudinally of the guide sleeve, as a unit. 10

In witness that I claim the foregoing I have hereunto subscribed my name this 9th day of March, 1923.

CLIFFORD SKLAREK.
